JAMES C. MEEM, OF BROOKLYN, NEW YORK, ASSIGNEE OF ONE-HALF TO FREDERICK L. CRANFORD, OF BROOKLYN, NEW YORK.

TUNNEL AND METHOD OF BUILDING AND SUBMERGING.

Application filed August 21, 1924. Serial No. 733,261.

To all whom it may concern:

Be it known that I, JAMES C. MEEM, a citizen of the United States, residing at Brooklyn, in the county of Kings and State 5 of New York, have invented certain new and useful Improvements in Tunnels and Methods of Building and Submerging, of which the following is a specification.

This invention relates to an improved 10 method and structure of subaqueous tunnels. Heretofore it has been customary in making subaqueous tunnels to build the tunnel in sections above water and subsequently to sink the sections and join them under 15 water. This is laborious, costly and uncertain. The submerging of the tunnel sections which is usually accomplished by admitting water to the interior of the sections has been accomplished with danger and disastrous 20 results due in part to the fact that when water is introduced into the section it tends to disturb the equilibrium causing water to flow suddenly to one end of the section and the section to sink end down. Attempts have 25 been made to control the sinking by floats, pontoons, tackle, staging, etc. but such control is cumbersome, expensive and generally unsatisfactory.

By the use of my invention I avoid the 30 necessity of joining tunnel sections under water by building the entire tunnel above water and subsequently sinking the same as a unit. This I accomplish without danger of sudden tilting or turning of the tunnel 35 about its axis or of subjecting it to injurious strains and I am also able to sink the tunnel without the aid of outside apparatus such as the floats, etc. above mentioned. For this purpose I have provided a novel and improved method and means for controlling 40 the sinking of the tunnel. In the case of short tunnels the entire tunnel may be submerged gradually and uniformly over its entire length. In the case of very long tunnels I preferably construct the tunnel so that 45 it has some flexibility and gradually sink the tunnel progressively along its length.

Those features of my invention which provide for an accurate control of the sinking 50 operation may also be employed where it is desired to sink a tunnel section and move the same into aline engagement with a previously laid section.

Numerous objects and advantages of my

invention will appear from the following 55 description taken in connection with the accompanying drawings wherein

Fig. 1 is a side elevation of a portion of the tunnel resting in its final position on the bed of the waterway and shows the upwardly extending buoyant shafts secured to 60 the tunnel at intervals along its length.

Fig. 2 is a longitudinal section of the tunnel taken on the line 2—2 of Fig. 3 65 looking in the direction of the arrow.

Fig. 3 is a section taken on the line 3—3 of Fig. 2 looking in the direction of the arrow.

Fig. 4 is a section taken on the line 4—4 of Fig. 2 looking in the direction of the arrow.

Fig. 5 is a section of the tunnel shell and the floating cradle upon which the shell is built.

Fig. 6 is a longitudinal approximately 70 central section of a partly completed portion of a tunnel showing a modified construction.

The tunnel structure and the method of building the same may vary considerably. In the form shown the tunnel comprises an outer metal shell lined inside with concrete and reinforced by a central and two side longitudinal girders of sufficient strength and rigidity to carry the weight of the tunnel safely over the length of 100 to 300 feet or more but subject to some flexibility (without impairment of strength) in lengths of 1000 to 5000 feet or more.

In building the tunnel there is first provided a cradle 10 having an upper supporting surface conforming to the contour of the bottom of the tunnel and of substantially the length of the entire tunnel. The cradle 10 may be a rough structure of timber or concrete or both. On this cradle there is 90 constructed the outside metal shell 11 of the tunnel which is formed of tubular sections joined end to end, there being provided at intervals along the top of the shell openings 12. When the shell 11 is built it is bulk-headed to prevent admission of water to the interior and the cradle 10 is scuttled or 95 wrecked leaving the shell 11 floating at the surface. This operation is preferably conducted in some quiet water adjacent the site. With the shell 11 floating the interior

structure of the tunnel is then completed, access for this purpose being gained through 100 the openings 12. The shell is lined with 105

concrete as shown at 15 and the tunnel is reinforced by a central longitudinal girder 16 and two side longitudinal girders 17.

Bulkheads 18 are provided adjacent to 5 and on opposite sides of each opening 12 and joining the two bulkheads adjacent to each opening is formed a central partition 19 which divides the space between the two bulkheads into two chambers 20. The par-

10 tition 19 may, if desired, be made of concrete and formed as a continuation of the concrete lining 15. Suitable hatchway or manhole covers are provided for the openings 12 and these covers are provided with 15 depending ribs 21 which extend across the openings 12 and engage the upper edges of the partitions 19 at the openings so as to effectively seal from one another the chambers 20 at opposite sides of the partitions.

20 There is then erected around each of the openings 12 a buoyant shaft 22 which is of sufficient length to extend above the surface of the water when the tunnel has been sunk to its final position. These shafts are se-

25 cured to the tunnel by a bolt and flange connection which forms a water tight joint and the shafts are guyed to the tunnel by cables 24 provided with adjusting turn buckles 25. While of considerable volume the shafts 22 30 are of very light construction and depend for their stability and strength on light internal bracing 26 and the guys 24.

Valves 27 are provided in each of the 35 chambers 20 and these valves are operated from the top of the shaft 22 by handles 23 which are connected to the valves by rods 28 which extend through the tunnel casing and through the shaft 22. Valves 27 are 40 designed to permit water to enter the chambers 20 from outside the tunnel through pipes 30. The chambers 20 communicate with the interior of the shaft 22 through pipes 31 located at opposite sides of the partition 19 and rib 21 and extending through 45 the manhole cover 35. Flow through the pipes 31 is controlled by means of a valve 36 located in the shaft 22 and operated from the top of the shaft by means of a rod 37 and handle 38.

50 While I have described the building of the interior structure of the tunnel and the attachment of the shafts 22 as being performed after the cradle 10 has been removed it will be understood that these operations may be conducted while the tunnel is still on the cradle and the cradle may be wrecked or scuttled at any time after the tunnel has become self-supporting.

55 When the tunnel structure above described has been completed and the bed of the waterway suitably prepared for the reception of the tunnel by dredging to the proper depth and grade and the laying if required of the sills 39, the tunnel is floated to a position 60 over its final bed and the valves 27 and 36

are opened. The chambers 20 are first flooded by water entering through the pipes 30 and subsequently water enters the shafts 22 from the chambers 20 through the pipes 31. As a result the tunnel sinks easily and evenly to its bed. As the tunnel sinks more of the buoyant shafts 22 become submerged and this acts as a check to the sinking requiring an additional quantity of water in the shaft to continue the sinking. The 70 valves permit a perfect control of the flow of water as desired into either or both of the chambers 20 and shaft 22 at the various chambers and shafts along the length of the tunnel, permitting the tunnel to be sunk 75 evenly along its length and the shafts to be maintained in an upright position. The partitions 19 prevent the water in the tunnel from flowing all to one side of the tunnel and so turning the tunnel on its axis and 80 the bulkheads 20 prevent the water in the tunnel from flowing all to one end of the tunnel and causing the tunnel suddenly to tilt on end.

In the case of short tunnels the valves at 90 all of the shafts 22 are opened simultaneously and each valve adjusted as required from time to time so that all parts of the tunnel are allowed to sink evenly at the same time. In the case of very long tunnels which have a certain amount of flexibility the valves at or near one end of the tunnel may be opened first, allowing that 95 end of the tunnel to sink gradually and subsequently the remaining valves opened so that the tunnel sinks to its bed progressively from one end to the other. Tunnels built and sunk in this manner may be adapted to 100 horizontal curves of long radius and gradual changes in grade without impairment of 105 strength.

Should it be desired to lift the tunnel or shaft after its first submergence this may be done by pumping down the water in its shaft 22. When the tunnel is in its proper position on the bed the entire tunnel may be flooded to insure proper seating. Suitable valves (not shown) may be provided for this purpose. The valves 36 are then permanently closed, such of the shafts 22 as it is not desired to retain as a permanent part of the tunnel are unbolted from the tunnel by divers and are removed together with the guys 24, valve rods and handles, valves 27 and all openings through the tunnel wall suitably closed. The tunnel is unwatered, bulkheads 18 removed and the tunnel back filled.

In Fig. 1 I have shown a portion of the 110 tunnel resting on the bed of the waterway. The end portions of the tunnel (not shown) may be joined to the tunnel proper by any suitable method. In cases where the end portions are vertical shafts extending above 115 the surface of the water, these portions may, 120

in certain cases, be joined to the tunnel proper after it has been sunk and in other cases the entire tunnel complete with the end portions joined may be built at the surface and sunk as a unit.

My improved method of controlling the sinking operation may also be employed in the laying of tunnels which are composed of sections which are successively sunk and

joined to the portion of the tunnel previously laid. Fig. 6 shows portions of two adjoining tunnel sections 50 and 51. The section 50 having been sunk and moved into engagement with the previously laid section

51. The casing 52 of each section is flared at one end as shown at 54 for a distance of from 25 to 50 feet and is adapted to receive the unflared end of an adjacent section. Bulkheads 55 are preferably employed to

close the adjoining ends of the sections until the joint between the section is sealed. The longitudinal members 57 of the central and side girders are extended through the bulkhead so that the longitudinal member

25 of one section will abut with the corresponding longitudinal member of the other section when the sections are in their final position. The cross members 58 of the girders however stop at the bulkheads.

30 After the section 51 has been laid the section 50 is lowered to a position slightly in front of and in approximate alignment with the section 51. The sinking is stopped just before the section 50 reaches the bottom by

35 closing the valves 36. The section 50 is then moved toward the section 51, the flared end 54 guides the section 50 to the position shown in Fig. 6 and section 50 is then allowed to sink to position on the bottom or to sills 39

40 if desired. The joint between the sections is then sealed in any appropriate manner. The bulkheads 55 are removed, abutting members 57 are secured to one another by tie-plates, the girder construction completed

45 and made continuous by adding cross members 58 at the joint and the space between the linings of the sections filled in with concrete so as to make the lining of the tunnel continuous.

50 I claim:

1. The method of sinking a tunnel having upwardly extending buoyant shafts at intervals along its length, in such a manner that the sinking of the tunnel or a part thereof may be regulated or arrested during all stages of the sinking operation, which method consists in gradually applying weights at intervals along the length of the tunnel and maintaining said weights in

60 their positions relative to the tunnel, whereby an approximate balance is maintained,

during the sinking operation, between the increasing weight of the tunnel and the increasing buoyancy due to the progressive immersion of the buoyant shafts.

65

2. The method of sinking a subaqueous tunnel which is provided with upwardly extending buoyant shafts at intervals along the length of the tunnel which method comprises gradually admitting water to the interior of said shafts so as to maintain an approximate balance between the changing weight due to the admission of water and the changing buoyancy due to the progressive immersion of the buoyant shafts.

70

3. A tunnel structure formed to float and provided at spaced intervals along its length with removable buoyant shafts of light weight and valve connections for admitting water to the interior of said shafts.

80

4. A tunnel structure comprising bulkheads along its length for providing spaces at intervals along its length, light buoyant shafts extending upwardly from the tunnel and respectively communicating at their ends with the spaces between the bulkheads, and valve connections for admitting water to said spaces and to the interior of said shafts.

85

5. A tunnel structure comprising bulkheads along its length for providing spaces at intervals along its length, central vertical partitions in said spaces between said bulkheads and extending in the direction of the tunnel, buoyant shafts extending upwardly from the tunnel and respectively communicating at their ends with the spaces between the bulkheads, and valve connections for admitting water to said spaces and to the interior of said shafts.

90

6. A tunnel structure comprising bulkheads along its length for providing spaces at intervals along its length, buoyant shafts extending upwardly from the tunnel and respectively communicating at their ends with the spaces between the bulkheads, and valve connections for admitting water to said spaces and from said spaces to said shafts.

105

7. A tunnel structure comprising bulkheads along its length for providing spaces at intervals along its length, buoyant shafts extending upwardly from the tunnel and respectively communicating at their ends with the spaces between the bulkheads, valve connections for admitting water to said spaces, other valve-connections for admitting water from said spaces to said shafts, and means extending above the water level for controlling said valve connections.
